PACKING FOR FRAGILE ARTICLES

Stephen J. Cox, Westfield, N. J., assignor to Packing Products Corporation, New York, N. Y., a corporation of Delaware

Application July 21, 1931, Serial No. 552,144

15 Claims. (Cl. 217—26.5)

The improvements relate to packing means for eggs and other fragile articles adapted to be inserted in cartons, boxes, crates or other containers and to hold in position and protect the same 5 therein. More particularly, they relate to packing of this class made of sheet material molded to form cups or holders to receive the said articles and to form in the outer container what is known as a filler, so that the articles are held thereby in position in the container and spaced from each other and from the walls thereof in such manner that they are protected against breakage. The improvements, however, may be employed in containers or carriers adapted to be used without an 10 outer container, and for other purposes.

Packing of this kind is now produced by what is known as the pulp sucking process, in which usually a drum having foraminous forms on its periphery and suction maintained in its interior 20 is rotated so that its lower segment passes through a bath containing fibrous material, such as wood pulp, the fibres in the bath being drawn by the suction against the forms and molded thereon to the desired thickness to form a sheet of material 25 corresponding in contour to the forms. This sheet is then pressed on the forms by complementary forms carried by another drum or endless chain, and removed from the first drum thereby, or by other means, and dried.

This method, while it is highly efficient and produces packing of most excellent character, has its limitations in the matter of the shape and depth of the cups or other article holding recesses, since the sheets must be such that they can be 30 removed freely from the first forms and as freely deposited on the second or drying forms, and therefore if recesses or projections have more than a relatively shallow depth, and do not flare outwardly at all points they will cling to the 35 forms, resist removal and become distorted or torn. To overcome this difficulty, packing has been devised in which shallow projections or recesses are formed with fold lines on which they must be folded to form cups or holders of the required depth. There are, however, various objections to this form, one of which is that the cups or holders are not preformed in their final shape, and therefore have a tendency to spread at all 40 times, release the articles placed therein or permit them to move around and become damaged in handling or transportation. Nor is this tendency remedied by the outer carton or container, which in most cases, and always in the case of eggs, must be of inexpensive construction, which 45 requires that they be made of thin sheet material,

usually paper, which spreads or bulges easily under the pressure of the eggs within and the pressure and distorting strains of packing, transportation and handling, the smallest number of eggs packed in one box or carton being usually one dozen, in two rows of six each, and these cartons being frequently stacked or packed in large containers, one upon another. Such folding fillers are also unadapted for use without an outside box or carton, since they have a tendency to unfold 10 at all times and release the articles therein. A shallow nonfolding filler, however, is not satisfactory, and permits breakage, since there is nothing to protect the outer part of the article projecting therefrom against pressure, shocks or 15 strains, and when cartons are superposed one upon another—sometimes five tiers in height—the pressure of the superposed cartons and their contents is borne almost wholly by the articles themselves. The filler must therefore extend 20 from top to bottom of the article and be of sufficient strength to substantially support such pressure. Again, in handling the cartons, the pressure of the hand of the person handling them is exerted on the upper part of the carton as well as 25 the bottom, and unless the filler or holder is such as to receive and resist this pressure, it is exerted on the eggs or other articles to their frequent damage.

The primary object of the present improvements is to produce a packing of the character indicated in which the article holding cups or recesses are preformed in their final shape and are therefore relatively rigid and will hold and protect the articles against all ordinary pressures 30 and strains, but which can be made in shallow form by the pulp sucking or similar method, and which at the same time is provided with means for resisting and protecting the article against pressure on all sides. Another object is to provide an open space at one side of the filler which will permit the dealer and purchaser to inspect the eggs without removing them therefrom, one side above the middle being exposed to view when the carton or the filler constituting a carton is 35 opened. This is accomplished by molding the cups or holders in their final form, and at the same time molding with them a connecting member between each row of cups and provided with hinge lines permitting them to be squeezed 40 together to form a very narrow partition extending to the tops of the eggs or other articles, and, if desired, to the bottoms thereof, so that when the sheet is compressed and placed in a box or 45 carton, or caused to form substantially such a 50

55

box or carton, the packing will have the required width, and the cups or holders will not be distorted in any way, but will remain in their original form and retain the natural strength and 5 rigidity of the material. Other objects and advantages will be apparent to those familiar with the manufacture and use of packing of this general character.

Three embodiments of the improvements are 10 illustrated in the accompanying drawings, in which—

Fig. 1 is a transverse vertical section of a packing filler embodying the improvements;

Fig. 2 is a view of the packing shown in Fig. 1, 15 as it is molded and before being compressed;

Fig. 3 is a view similar to Fig. 1 of a modification;

Fig. 4 is a view similar to Fig. 1 of another modification;

Fig. 5 is a view similar to Fig. 2 of the embodiment shown in Fig. 4;

Fig. 6 is a view similar to Fig. 1 of the form shown in Figs. 4 and 5 adapted for use in crates or large containers, or to form a box or carton 25 in itself; and

Fig. 7 is a plan of the embodiment shown in Fig. 2.

In the form illustrated in Figs. 1, 2 and 7, the packing consists of a non-planiform sheet of 30 molded material comprising a row of relatively rigid egg-receiving cups 1 separated by projecting members 2 interposed between the cups and conforming approximately on their vertical sides to the curvature of the egg. These cups have 35 supplemental recesses 3 to protect the egg from the bottom of the carton 4, or other support and circumferential medial ribs 5 to further protect them. These parts are all preformed, preferably by the pulp sucking, felting process, and constitute rows of complete egg-receiving cups which 40 will resist pressure from within and from without and maintain their original and finished shape and arrangement at all times and against all ordinary strains. Connecting each row of 45 cups with the next is an intermediate partition-forming member comprising straight portions 6 hinged together at their inner edges at 7 and strengthening and egg-dividing curved projections 8, each member consisting of the parts 6 and 8 being joined to the upper edge of and adjacent cup by the hinge 9.

In order to place the member thus formed in a carton or other container, it is only necessary to bend the intermediate portions upwardly and 55 squeeze them together, permitting them to turn on their hinges 7 and 9, until they have assumed the position shown in Fig. 1, then insert them in the outer container, when they are ready to receive eggs or other articles. In the form of Fig. 3, the cups are of the same form, but are connected by a partition consisting of straight members 10, 11 and 12, formed by first molding them flat and then folding them at 9', 13, 14 and 60 15, and squeezing them together, so that a partition extending from top to bottom of the eggs, and preferably a little beyond them, is formed.

The form shown in Fig. 4 is first molded flat, as shown in Fig. 5, with the partition-forming members hinged at 9'', 15, 16 and 17. These 70 partition-forming members, 18, 19, 20 and 21 when folded, as shown in Fig. 4, form a partition, in which there are sheets or flat strips of material extending from top to bottom and a flat sheet 75 on each side connecting their upper edges with

the cups. The strips 19 and 20 may be provided with strengthening grooves 22, if desired.

In Fig. 6, substantially the same form as that of Figs. 4 and 5 is shown, adapted to be used in an outer receptacle intended to receive more than two rows of eggs. The outer member 23 of the end partition is disconnected at its outer edge and adapted to be folded, with the longer strip 24, over the bottoms of the two cups, and the outer, similar members 25 and 26 with 27 on the opposite side are adapted to be folded over the tops, as indicated by arrows, so that in this manner a complete carton and carrier for two rows of eggs, except for the end closures, may be formed. These strips 23 may also be turned up if desired to form an outer wall extending to twice the height of the middle partition.

All the forms shown, including the preferred form of Figs. 1 and 3, may be made with any desired number of rows of cups, and when made up in rows of six each row having six cups, as in the ordinary standard crate, they will take the place of both the flats and the fillers commonly used.

The projections 8 of the preferred form may 25 be omitted if desired and flat walls like those of the other forms, or other non-planiform walls employed. On the other hand, the other forms may have such projections or may be corrugated or given any other desired conformation. The 30 projections 8 (see Fig. 7) emerge from their connecting portions and taper upwardly on all sides, so that they will hold the eggs in upright position, separate them from other eggs in the same row and from eggs in adjacent rows, 35 and at the same time give strength and rigidity to the partitions in which they are formed and assist them in protecting the eggs against vertical pressure and other shocks and strains.

In Fig. 1 an outer box or carton 4 of ordinary 40 form is shown, to illustrate the position of the packing therein and its relation thereto. Any outer container, however, may be employed, and, as before noted, the improvements may be employed without an outer carton or in the standard 45 crate of commerce, in which they will take the place of the flats and fillers now in common use.

What I claim is:

1. In a packing of the character described, a 50 row of molded preformed non-compressible cup-like holders of sheet material composed of fibres assembled to form a non-planiform sheet having the dimensions and contour of said cups, and connecting portions between said preformed cups 55 integral therewith in extended form and forming therewith a continuous sheet, but provided with hinge portions separating it into sections which when folded on said hinge portions will lie in substantially parallel planes and extend above the upper edges and between the holders when compressed.

2. In a packing of the character described, a 60 row of molded preformed non-compressible cup-like holders of sheet material composed of fibres forming a non-planiform sheet having the dimensions and contour of said cups, and connecting portions between said preformed cups integral therewith in extended form and forming therewith a continuous sheet, but provided with hinge 65 portions separating it into sections which will lie in substantially parallel planes and extend vertically away from the upper edges of the cups and between the holders when compressed.

3. The herein-described method of making a 75

filler packing which consists in molding a sheet of fibrous material to form upright relative rigid, complete article receiving cups therein conforming approximately to the article to be received thereby and relatively flat connecting portions between the cups having hinge portions connecting sections thereof and flexible portions connecting the same with the cups, then compressing the said connecting portions and causing them to assume upright positions between the cups.

4. In a packing of the character described a row of molded preformed completed cup-like holders of sheet material composed of fibres forming in normal position a sheet having the dimensions and contour of said cups, and connecting portions between said preformed cups integral therewith in extended form, but provided with hinge portions separating them into sections which will lie in substantially parallel planes and extend above the upper edges of the cups and between them when compressed, said connecting portions having a width between their hinges substantially equal to the depth of the cups, and when compressed and thus caused to assume upright positions between the cups adapted to extend to the top of an article the lower portion of which is held in the cup.

5. In a packing of the character described a row of molded preformed upright finished cup-like holders of sheet material composed of fibres forming a sheet having the dimensions and contour of said cups, and connecting portions between said preformed cups integral therewith in extended form, but provided with hinge portions separating them into sections which will lie in extended position and extend above the upper edges of the cups and between them and from said cups to the extremity of an article supported in and extending beyond the same when compressed to form partitions and separators between the cups and supporting and protecting members.

6. In a packing of the character described, a row of molded preformed cup-like holders with approximately upright walls of sheet material composed of fibres forming a sheet having the dimensions and contour of said cups, and connecting portions between said preformed cups integral therewith in extended form, but provided with hinge portions separating them into sections which will lie in substantially parallel planes and extend above the upper edges of the cups and between them when compressed, said connecting portions having thereon projections extending over the cups when said portions are in upright compressed position.

7. In a packing of the character described, a row of molded preformed approximately upright cup-like holders of sheet material composed of fibres assembled to form a sheet having the dimensions and contour of said cups, and connecting portions between said preformed cups molded therewith in extended form, but provided with hinge portions, separating it into sections which will lie in substantially parallel planes and extend above the upper edges of the cups and between them when compressed and to the bottoms of said cups.

8. In a packing of the character described, a molded preformed cup-like holder of sheet material composed of fibres assembled to form a sheet having the dimensions and contour of said cup, and connecting portions between said preformed cups molded therewith in extended form, but provided with hinge portions separating it into sections which will lie in substantially parallel

planes and extend above the upper edges of the cups and between them when compressed and other members similar to said connecting portions on the outer sides of said cups and connected therewith.

9. In a packing of the character described, a molded preformed cup-like holder of sheet material composed of fibres assembled to form a sheet having the dimensions and contour of said cup, and connecting portions between said preformed cups molded therewith in extended form, but provided with hinge portions separating it into sections which will lie in substantially parallel planes and extend above the upper edges of the cups and between them when compressed and other members similar to said connecting portions on the outer sides of said cups and connected therewith, said last-named members being adapted to be folded over the tops and bottoms of said cups to enclose the same at top and bottom.

10. In a packing of the character described, a row of molded approximately upright preformed cup-like holders of sheet material having the dimensions and contour of said cups, and connecting portions between said preformed cups integral therewith in extended form, but provided with hinge portions separating them into sections which when folded on said hinge portions will lie in substantially parallel planes and extend above their junction with the cups and at least approximately to the extremity of an article supported in and extending beyond the same to form article separating and protecting and vertically extending external pressure sustaining members.

11. In a packing of the character described, a row of molded preformed substantially rigid cup-like holders having walls fixed in position by said molding to support an article in upright position formed of sheet material composed of fibres assembled to form a non-planiform sheet having the dimensions and contour of said cups, and connecting portions between said preformed cups integral therewith in extended form and forming therewith a continuous sheet, but provided with hinge portions separating them into sections which will lie in substantially extended position and extend above the upper edges and between the holders and to the top of an article therein projecting above the same when compressed, said connecting portions having hinge connections with the holders and being foldable intermediate said flexible connections.

12. In a packing of the character described, a row of molded preformed substantially rigid cup-like holders having walls fixed in position by said molding to support an article in upright position formed of sheet material composed of fibres assembled to form a non-planiform sheet having the dimensions and contour of said cups, and connecting portions between said preformed cups integral therewith in extended form and forming therewith a continuous sheet, but provided with hinge portions separating them into sections which will lie in substantially parallel planes and extend above the upper edges and between the holders when compressed, said connecting portions having hinge connections with the holders and having lateral projections thereon.

13. In a packing of the character described, a row of molded preformed substantially rigid cup-like holders having walls fixed in position by said molding to support a portion only of an article thereon formed of sheet material composed of fibres assembled to form a non-planiform sheet

having the dimensions and contour of said cups and connecting portions between said preformed cups integral therewith in extended form and forming therewith a continuous sheet, but provided with hinge portions separating them into sections which will lie in extended position and extend above the upper edges and between the holders and at least approximately to the extremity of the article supported thereby when compressed, said connecting portions having flexible connections with the holders.

14. In a packing of the character described, a row of molded preformed substantially rigid cup-like holders having walls fixed in position by said molding to support a portion only of an article thereon formed of sheet material composed of fibres assembled to form a non-planiform sheet having the dimensions and contour of said cups, and connecting portions between said preformed cups integral therewith in extended form and forming therewith a continuous sheet, but provided with hinge portions separating them into sections which will lie in extended position and

extend above or below the upper edges and between the holders and at least approximately to the extremity of the article supported thereby when compressed, said connecting portions having flexible connections with the holders.

15. In a packing of the character described, a row of molded preformed substantially rigid cup-like holders having walls fixed in normal position to support a portion only of an article thereon and formed of sheet material composed of fibres assembled to form a non-planiform sheet having the dimensions and contour of said cups, and connecting portions in extended form between said preformed cups integral therewith and forming therewith a continuous sheet, but provided with hinge portions separating them into sections which will lie in extended position and extend above or below the upper edges and between the holders and at least approximately to the extremity of the article supported thereby when compressed, said connecting portions having flexible connections with the holders.

STEPHEN J. COX.
